UNITED STATES PATENT OFFICE.

CORNELIUS JAMES CALLAGHAN, OF COLUMBUS, OHIO.

WINDOW OR DOOR STRUCTURE.

Application filed May 3, 1927. Serial No. 188,541.

The invention relates to window or door structures and more particularly to an apparatus for providing in the window or door structure a transom.

- 5 An important object of the invention is to provide a structure of this character which may be directly attached to the door or window and which may be formed entirely from metal.
- 10 A further object of the invention is to provide a novel and improved transom frame structure and means for mounting the transom therein.

15 A further and more specific object of the invention is the provision of a device of this character, which is so constructed that the transom element may be readily removed at any time to permit replacement of the pane or cleansing thereof.

- 20 A still further object of the invention is to provide a transom structure having means connecting it to its pivots and maintaining separable frame sections in assembled relation, whereby upon removal of the 25 transom, the parts may be separated to facilitate cleansing or replacement thereof.

These and other objects I attain by the construction shown in the accompanying drawings, wherein for the purpose of illustration is shown a preferred embodiment of my invention and wherein:

Figure 1 is a fragmentary front elevation of a door having a transom structure applied thereto in accordance with my invention;

Figure 2 is a vertical sectional view therethrough on the line 2-2 of Figure 1;

Figure 3 is a section on the line 3-3 of Figure 1;

40 Figure 4 is a section on the line 4-4 of Figure 3;

Figure 5 is a section on the line 5-5 of Figure 4;

Figure 6 is a section on the line 6-6 of Figure 5;

Figure 7 is a detail side elevation of one of the pivots;

Figure 8 is a detail sectional view showing a slightly modified form of outside frame plate;

Figure 9 is a detail sectional view showing the manner of applying the transom to a window, the glass of which is completely framed.

55 Referring now more particularly to the drawings, the numeral 10 generally designates the upper portion of the door or window frame structure including side members 11 having arranged therebetween a pane 12, which does not extend to the upper ends of 60 the side members. In accordance with my invention, I provide a transom frame structure constituting a cross member for the door or window frame consisting of an outer frame and a transom pivotally mounted 65 therein.

The outer frame includes side plates 13 and 14 adapted to be arranged at opposite sides of the door and have their end edges contacting the upper ends of the side members 11. Between the side members, the plates 13 and 14 are formed with openings, the upper and lower edges of which are spaced from the upper and lower edges of the plates. The upper edge of the opening 70 of the plate 13 is provided with an inwardly and downwardly deflected flange 15, while the bottom edge thereof is provided with a horizontal flange 16 adapted to extend to the lower edge of the opening of the plate 80 14 and provided at its free end with an upwardly and inwardly deflected terminal flange 17. The side edges of the opening of the plate 14 have inwardly directed parallel flanges 18, the free edges of which engage 85 against the inner face of the plate 13 at the edges of its opening and the adjacent faces of which contact the flanges 15 and 16 and the terminal flange 17 of the flange 16 and may be secured thereto, if so desired. The 90 upper and side edges of the plates 13 and 14 may be provided with overlapping flanges, as designated at 19 and 20. The lower edges of the plates between the side edges of the side members 11 may be provided with inwardly and downwardly extending molding flanges 21, the terminal portions 22 of which are adapted to receive therebetween a pane of glass 12, as indicated in Figure 2, or the lower edges between these side members may be secured to a cross member 23, 100 in which the upper edge of the glass pane 12 is mounted.

The transom proper comprises a glass receiving frame for the transom pane 24, which is in the form of a pair of rectangular frame elements 25 L-shaped in cross section and adapted to telescopically engage one another and produce a rectangular frame substantially U-shaped in cross section. Those arms 26 of the L-shaped members which form the sides of this frame are 105 110

provided with reverted flanges 27 which are at an acute angle to the arms 26 and form a molding for the glass 24. The upper flange 27 of one of the members 25 and the lower flange 27 of the other of the members 25 engage with the flange 15 and terminal flange 17 of the flange 16 when the transom is vertically disposed. The flanges 27 at the ends of the frame come into very close proximity to the flanges 18 at the edges of the opening of the plate 14. The arms 26^a at the ends of the transom frame are provided with aligned apertures 28 at opposite sides of their centers, for a purpose presently to appear.

Each flange 18 is formed at its center with an opening 29 rotatably receiving a pivot 30. This pivot 30 at its inner end is directed through an opening 31 in a member 32 having arms 33 flatly engaging the outer faces of the arms 26 of the transom glass frame members 25 to prevent separation thereof. The pivot 30 has a head fitting between the arms 33 and surrounding the pivot between this head and the base 34 of the member 32 is a washer 35 of spring material having outwardly extending diametrically opposed arms 36 of slightly less width than the space between the arms 33. The ends of the arms 36 have right angularly deflected portions 37 adapted to enter the openings 28 of the arms 26^a of the transom glass frame, so that this frame is held against movement in its own general plane with relation to the pivot. The ends of these arms are accessible when the transom frame is horizontally arranged and may be sprung back to disengage the terminals 37 from the openings to permit the frame to be removed from its pivots.

Attention is directed to the fact that when this frame is removed from its pivots, all that is necessary to resolve the same into its component parts is to pull the frame elements 25 apart.

One of the pivots 30 has secured to its outer end an arm 38 which is held against rotation with relation to the pivot and provided with a longitudinal slot 39. Pivoted upon the corresponding flange 18 is a bell 50 crank lever 40, one arm of which has a pin 41 extending into the slot 39 and the opposite end of which extends through a slot 42 formed in the plate 14. The outer end of this arm is provided with an operating 55 handle 43 and this end of the arm may be held in adjusted positions by engaging the same in vertically spaced coves 44 formed along one edge of the slot 42.

It will be obvious that by shifting the 60 bell crank lever 40, the transom may be shifted and that by engaging the operating arm of the bell crank in a selected cove, the transom may be held in adjusted positions.

A structure of this character may be very 65 readily applied to a door or window frame

and will provide for ventilation without the necessity of opening the same. A window may be provided both at its upper and lower ends with such transom structures and, if so provided, may be made stationary within 70 its frame, eliminating the necessity for weather-stripping and at the same time making provision for proper ventilation.

Since the construction hereinbefore set forth is capable of a certain range of change 75 and modification without materially departing from the spirit of the invention, I do not limit myself to such specific structure except as hereinafter claimed.

I claim:

1. In a transom or the like, an outer frame, an inner pane receiving frame formed in telescopically engaging separable sections providing when in assembled relation a channel receiving the edge of the pane 80 and pivots connecting the outer frame and inner frame including means preventing separation of the sections.

2. In a transom or the like, an outer frame, an inner pane receiving frame formed in telescopically engaging separable sections providing when in assembled relation a channel receiving the edge of the pane and pivots connecting the outer and inner frames at the side ends thereof having arms engaging oppositely facing faces of the sections of the pane frame to prevent separation thereof and means associated with the pivots locking the frame ends against longitudinal movement with relation to the pivot.

3. In a transom or the like, an outer frame, an inner pane receiving frame formed in telescopically engaging separable sections providing when in assembled relation a channel receiving the edge of the 100 pane, pivots connecting the outer and inner frames at the side ends thereof having arms engaging oppositely facing faces of the sections of the pane frame to prevent separation thereof and spring arms carried by each 110 pivot having at their ends angular portions extending through aligned openings formed in the ends of the sections of the pane frame to maintain said sections against longitudinal movement with relation to the pivots.

4. In a transom structure or the like, plates adapted to engage at their ends against opposite faces of the side members of a door structure and having aligned openings formed therein, flanges extending inwardly from the end edges of one of said plates and engaging the other thereof, pivots mounted in said flanges, a pane frame mounted upon said pivots and flanges at the upper and lower edges of the opening of the other 125 of the plates having portions engaging the upper outer edge and lower inner edge of the pane frame in one position thereof.

5. In a transom structure or the like, plates adapted to engage at their ends 130

against opposite faces of the side members of a door structure and having aligned openings formed therein, flanges extending inwardly from the end edges of one of said plates and engaging the other thereof, pivots mounted in said flanges, a pane frame mounted upon said pivots, a flange extending inwardly and downwardly from the upper edge of the opening of the other of said plates, a horizontally extending flange projecting from the lower edge of the opening of the last named plate and engaging the lower edge of the opening of the first named plate when the plates are in assembled relation, the last named flange having at its edge a terminal flange which extends upwardly and inwardly, said terminal flange and the flange at the upper edge of the opening engaging the lower inner and upper outer edges of the pane frame respectively when said frame is in one position.

6. In a transom or the like, an outer frame, an inner pane receiving frame formed in two rectangular frame elements L-shaped in cross section, telescopically engaging to produce a rectangular frame U-shaped in cross section for the reception of the outer edges of a pane, the telescopically engaging arms of the L-shaped members having openings aligning when the members are in assembled relation and pivots carried by the outer frame and embodying spaced arms engaging the outer faces of the remaining arms of the L-shaped members to prevent separation thereof and means carried by said pivots and engaged in the aligned openings for preventing longitudinal movement of the frame members upon the pivots.

7. In a transom or the like, an outer frame, an inner pane receiving frame formed in two rectangular frame elements L-shaped in cross section, telescopically engaging to produce a rectangular frame U-shaped in cross section for the reception of the outer edges

of a pane, the telescopically engaging arms of the L-shaped members having openings aligning when the members are in assembled relation, pivots carried by the outer frame and embodying spaced arms engaging the outer faces of the remaining arms of the L-shaped members to prevent separation thereof and spring arms carried by each pivot having terminal portions to enter the openings of the frame element and prevent longitudinal movement thereof with relation to the pivots.

8. In a transom structure or the like, plates adapted to engage at their ends against opposite faces of the side members of a door structure and having aligned openings formed therein, flanges extending inwardly from the end edges of one of said plates and engaging the other thereof, pivots mounted in said flanges, a pane frame mounted upon said pivots and flanges at the upper and lower edges of the opening of the other of the plates having portions engaging the upper outer edge and lower inner edge of the pane frame in one position thereof, the lower edges of said plates having downwardly converging portions the free edges of which are adapted to engage and support a pane.

9. A device as set forth in claim 1, wherein means are associated with the pivots locking the frame ends against longitudinal movement with relation to the pivot.

10. A device as set forth in claim 1, wherein means are associated with the pivots locking the frame ends against longitudinal movement with relation to the pivot, accessible in one position of the inner frame for movement to an operative position to thereby permit removal of the inner frame.

In testimony whereof I hereunto affix my signature.

CORNELIUS JAMES CALLAGHAN.
